LAWN SPRINKLER

Eugene L. Boyd, 1930 Emerald St., San Diego, Calif.

Filed Aug. 27, 1962, Ser. No. 71,464

Term of patent 14 years

(Cl. D91—1)

FIG. 1

FIG. 2

FIG. 3

FIG. 1 is a side elevational view of a lawn sprinkler showing my new design;

FIG. 2 is a front elevational view thereof; and

FIG. 3 is a top plan view thereof.

The side opposite that shown in FIG. 1 is a mirror image thereof.

The dominant features of my design reside in the portions shown in the full lines.

I claim:

The ornamental design for lawn sprinkler, as shown and described.
